UNITED STATES PATENT OFFICE.

CECIL EDWARD LLOYD, OF PENSACOLA, FLORIDA.

ADJUSTABLY-ENGAGING SUPPORT.

1,323,599.

Specification of Letters Patent.

Patented Dec. 2, 1919.

Application filed June 19, 1919. Serial No. 305,236.

To all whom it may concern:

Be it known that I, CECIL E. LLOYD, a citizen of the United States, and a resident of Pensacola, in the county of Escambia and State of Florida, have invented certain new and useful Improvements in Adjustably-Engaging Supports, of which the following is a specification.

My present invention relates generally to 10 adjustably engaging supports capable of use either as ironing tables, cot beds, and the like, and particularly to an arrangement of that nature including a frame and a body member swingingly disposed in the frame, these 15 parts being flexibly connected to one another in such manner as to present relatively opposing portions acting as a clamp to engage sections of a table, automobile running board, and the like, and my object is the 20 provision of an arrangement including certain novel connections whereby to automatically compensate for difference in the thickness of engaged portions of a table, as well as the height of such portions from a floor 25 or roadway so as to adapt the arrangement to an interchange of uses, such as for instance those above mentioned.

As above stated my invention resides particularly in novel connections and results in 30 enabling the shifting of the fulcrum between the frame and the body member or board, and proposes connections which bring about such shifting movement in a simple, ready and effective manner such as to work 35 in opposition to the shiftable fulcrum forming means or connections when the support is in engaged position for the purpose of increasing its stability in use.

In the accompanying drawings illustrating 40 my present invention and forming a part of this specification,

Figure 1 is a perspective view illustrating the practical application of my invention to a table, for use as an ironing board,

Fig. 2 is a similar view illustrating a practical application of my invention to the running board of an automobile for use as a cot bed,

Fig. 3 is a partial longitudinal section 50 through the cot bed of Fig. 2,

Figs. 4 and 5 are longitudinal sections through the arrangement as an ironing board respectively in connection with a high and a low table,

Fig. 6 is a transverse section taken on line 6-6 of Fig. 4,

Fig. 7 is a detail perspective view of the combined adjustment and supporting crank, and

Fig. 8 is a detail perspective view of one 60 of the bearing brackets.

Referring now to these figures and particularly to Fig. 1, my invention proposes an adjustably engaging support, here illustrated as an ironing table, and including a 65 body member or board 10 which in the inactive position extends between and in flat-wise relation with, the side rails 11 of a frame the opposite ends of which are entirely free, these side rails being connected 70 by cross braces 12 and being preferably beveled at one end as at 13, for engagement with the floor or ground. The opposite ends of these side rails have lower angular engaging surfaces 14, adjacent to which their 75 upper faces or edges support transversely alined bearing plates 15 for the offset extensions 16 of a crank hanger 17. The intermediate bar of this hanger is journaled in bearing brackets 18 transversely alined upon 80 the lower face of the body member or board 10 adjacent to one end and at this end it will be noted by particular reference to Figs. 4 and 5, that the upper portion of the board is cut away adjacent to its extremity to 85 form a reduced support-engaging portion which in action opposes the downwardly facing engaging surfaces 14 of the side rails 11 of the frame.

It is obvious that by means of the crank 90 hanger 18 I form a shiftable fulcrum for the movement of the body member or board 10 with respect to its frame so that the effective engaging space between its reduced end and the engaging surfaces 14 of the frame side 95 rails may be varied to a considerable extent and still maintain these parts in approximately parallel relation. In this way, I provide for regulation or compensation as to table tops, engaged between the opposing 100 portions of the body member and its frame, of varying thicknesses.

In addition to the foregoing, a second crank connection is provided between the body member or board 10 and its frame, this 105 second crank being indicated at 19 with its central bar journaled in bearing brackets 20 transversely alined on the lower face of the board and with its offset extensions journaled in bearing brackets 21 transversely 110 alined upon the lower edges of the side rails 11. Thus the two crank connections between

the body member and its frame are spaced longitudinally of the latter and it will be noted that the offset of the crank 19 is considerably less than that of the crank 17, so that in the clamped position shown for instance in either Figs. 4, 5, 1 and 2, the two points of support work against one another as between the board and its frame whereby to coöperate with the clamping portions of 10 the board and frame in engagement with the table or other part in effectively holding the board in outstanding horizontal position.

It is equally obvious that, by virtue of the crank 19, which may be turned up or down, 15 the board and frame as provided by my invention may be adjusted to high or low tables and that the same construction may be adapted as a low down support for instance in the nature of a cot bed for use with 20 automobiles as seen in Fig. 2 in engagement with the side edge of the running board. In this latter construction the board is indicated at 10^a and may if desired, be in hinged sections foldable one upon the other 25 upon the hinges 21. The side rails 11^a of the frame in this form may also be in hinged sections foldable upon hinges 22 so that the appliance as a whole in folded position may be readily carried within the machine.

30 Referring again to Fig. 1 and also to Fig. 7, it will be noted that one of the offset extensions of the crank 19 has a squared extremity 24 arranged to be engaged by a crank handle 25 so that the crank 19 may be 35 readily shifted to adjust the board 10 with respect to its frame for the purposes above stated.

It is obvious therefore that my invention provides a practicable, efficient construction 40 of the present character capable of a wide range of adjustment as between tables, running boards, and the like of varying thicknesses and varying heights from the floor or ground, and is thus adaptable to a wide 45 range of use.

I claim:—

1. An appliance of the character described comprising a frame having angular engaging surfaces at one end, a body member or board in the frame having one end arranged 50 to oppose the said engaging surfaces of the frame and coöperate therewith to form a support engaging clamp, and a pair of crank connections between the board and the frame, one of which forms a working fulcrum for the board.

2. An appliance of the character described comprising a frame having angular engaging surfaces at one end, a body member or board in the frame having one end arranged 60 to oppose the said engaging surfaces of the frame and coöperate therewith to form a support engaging clamp, and a pair of crank connections between the board and the frame spaced apart lengthwise of the 65 board, one of which forms a movable fulcrum for the board, as described.

3. An appliance of the character described comprising a frame having support engaging portions at one end, a body member or 70 board in the frame having a reduced portion adjacent to the said engaging portions of the frame, a pair of cranks journaled in connection with the board and frame at longitudinally spaced points, one of which 75 cranks has a greater throw than the other and forms a movable fulcrum for the board, and a handle engaged with the other crank, for the purpose described.

4. An appliance substantially as described 80 comprising a frame, a board and swinging crank connections between said board and frame, one of which forms a working fulcrum for the board.

5. An appliance substantially as described 85 comprising a frame, a board and a pair of swinging crank connections spaced apart and connecting the frame and board substantially as set forth.

CECIL EDWARD LLOYD.
